UNITED STATES PATENT OFFICE.

JAMES HUNTER GRAY, OF LONDON, ENGLAND.

MONEY-TRAY.

SPECIFICATION forming part of Letters Patent No. 658,910, dated October 2, 1900.

Application filed November 13, 1896. Renewed November 29, 1898. Serial No. 697,803. (No model.)

To all whom it may concern:

Be it known that I, JAMES HUNTER GRAY, a subject of the Queen of Great Britain and Ireland, and a resident of 2 Brick Court, Temple, London, England, have invented certain new and useful Improvements in Money-Trays, of which the following is a specification.

The object of my invention is to provide money-trays which while being less costly than others, at the same time more readily enable coins to be picked up than rubber and other money-trays of the hitherto usual kinds. My money-trays also last longer than other flexible money-trays and can be readily renewed.

In order that my invention may be readily understood, reference is made to the accompanying drawings, wherein like letters of reference indicate corresponding parts throughout the several figures, and in which—

Figure 1 shows in sectional side elevation my improved money-tray, consisting of a rubber bag having an internal frame. Fig. 2 shows in sectional side elevation an alternative form of my improved money-tray in which the elastic surface is affixed on a shallow dish having an air-valve; and Fig. 3 shows in sectional side elevation a further alternative form of my improved money-tray, the elastic surface being attached to an open frame.

My invention consists, essentially, in the employment of one or more sheets of india-rubber, cloth, parchment, parchment-paper, or other suitable and sufficiently-elastic material, which I stretch to a sufficient extent and fix to a frame of suitable shape and dimensions, the arrangement being such that a layer of air is under said india-rubber or other material and acts as a cushion, so that when coins are being picked therefrom the fingers depress the portion immediately around the coin, and thereby the coin can be readily taken hold of even when the fingers are incased in a thick glove. If desired, the said india-rubber or other material may be caused to bulge outwardly—say by increasing the air-pressure—which still further increases the facility to pick up coins from the tray.

In carrying out my invention, and referring first to Fig. 1, I make a circular frame C, over and to which I stretch two sheets A of rubber or other suitable material, one on the top and one on the bottom of said frame, to 55 form my tray, so that said tray is reversible, as will be readily understood from the drawings, and the said sheets A are sufficiently elastic as to be readily depressed by the fingers when coins are being picked up therefrom. 60

In place of providing an upper and a lower sheet A, as above described, I may, Fig. 2, make the frame C with a bottom B, said bottom and frame being preferably integrally formed of metal in about the form of a plate 65 or shallow dish. Over the top of said dish I stretch the sheet A and fix it to the sides C, and, if desired, I may provide the said frame C with an air-valve V, so that the tray may be inflated and the upper and elastic surface 70 caused to bulge to a sufficient extent, about as shown, or I may employ the frame C only and stretch and fix the sheet A onto it, as shown in Fig. 3.

I do not confine myself to any particular 75 means or method of attaching the sheet A to the frame C. For example, the sheets A A in Fig. 1 may be separately fixed to the frame C by frictional contact or by means of cement or otherwise, or said sheets may be formed 80 integrally in the form of a circular bag, about as shown, and a split frame C inserted through a slit or opening at the side of said bag, or I may make the frame C in about the sectional 85 shape shown in Figs. 2 and 3, so that the rubber or other elastic sheet A, whose edges are for this purpose molded so as to form a thickened flange, may be sprung onto said frame.

Having now described my invention, what I claim as new, and desire to secure by Letters 90 Patent, is—

1. As a new article of manufacture, a money-tray consisting of a supporting-frame and an exposed sheet of material supported thereby at its edges leaving the body portion freely 95 suspended and having a degree of elasticity to permit the same to yield under the pressure of the fingers in picking up the coin.

2. A money-tray comprising a frame and an exposed sheet of material supported there- 100

by and having a degree of elasticity which will permit the same to be indented by the fingers independently at the several points of contact about the coin in picking up the same, substantially as described.

3. In combination in a money-tray, a supporting-frame and a flexible cover secured thereto and extending above the plane of its connection with the frame, substantially as described.

4. In combination in a money-tray, a supporting-frame, a cover distended into convex form and means for holding the cover distended while allowing the same flexion, substantially as described.

5. A money-tray consisting of a frame and a sheet of elastic material supported thereby,

5 said elastic material being pneumatically controlled.

6. In a device of the character described, 20 a tray, an air-valve in said tray, and a flexible air-tight cover secured over said tray, substantially as described.

7. In a device of the character described, 25 a tray having outwardly-flaring edges, an air-valve in said tray, and a resilient air-tight covering secured to the tray edges, substantially as described.

In witness whereof I have hereunto set my hand in the presence of two witnesses.

JAMES HUNTER GRAY.
